ARCH SUPPORTING SHOE

Charles L. Laible, Fort Thomas, Ky., assignor of
one-half to Horace C. Mayers, Cleveland, Ohio

Application February 19, 1931. Serial No. 516,947

18 Claims. (Cl. 36—71)

My invention relates to arch supporting shoes, and particularly to shoes provided with means for supporting the main arch of the foot.

It has been suggested in the prior art to provide a stirrup extending down from the sides of the heel portion of the shoe which carries the main arch of the foot in a hammock-like arrangement. Such stirrups, while alleviating fallen arches when the shoes are new, have the disadvantage that after the shoe has been worn for any extended period the stirrup tends to sag, and also to pull down the sides of the shoe close to the front end of the shoe counter. Such an embodiment of a freely suspended stirrup is illustrated in the Banks United States Patent No. 1,677,226, of July 17, 1928, and, as has been stated, has not met with any substantial success due to a tendency to sag and pull the shoe out of shape.

It is the object of my invention to provide an adjustable stirrup-like support either provided with adjustable lacing or with a resilient connection which will be supported from the shoe counter. Another object is to provide an arch support which can be conveniently secured in position during the normal manufacture of a shoe of any type. I shall describe my invention however, in connection with a shoe of the welt type. Another object is the provision of a stirrup arch support which extends under a split portion of the insole so that there will be no tendency for the stirrup adjustment to cause discomfort to the bottom of the foot of the wearer.

In the provision of an adjustable stirrup, it is my object to provide a support which, should it tend to sag down, may be adjusted and tightened up to provide a desired degree of arch support.

Another object of my invention is the provision of a support for the main arch which will not be in any way obvious to the wearer, which will avoid the necessity of metal plates or resilient pads, and which, in walking, will tend to spring up with the movements of the foot so as to support the arch during the normal muscular movements of the foot in walking.

The above objects and other objects to which reference will be made in the ensuing disclosure, I accomplish by that certain combination and arrangement of parts of which I have shown a preferred embodiment.

Referring to the drawing:—

Figure 1 is a perspective view from above, with the split portion of the insole and the sock

lining of the shoe thrown back to reveal the construction of the stirrup support.

Figure 2 is a longitudinal, vertical, sectional view of the shoe shown in perspective in Figure 1.

Figure 3 is a plan view of one side of the stirrup support.

In order to first explain the manner in which I insert my adjustable arch support during the manufacture of the shoe, I will first describe the operation of manufacturing a welt type shoe, which is the type of shoe with which my invention is particularly described herein.

The insole 1, which usually has a canvas facing 2, and in which I provide a split portion 3 extending from the heel end of the insole to the beginning of the ball of the foot, is tacked on the last.

The counter 4 is then fitted in the heel end of the upper, and the finished upper 5, which has the lining 6 stitched to it along its upper edge, is pulled over the last and secured along the sides of the welt strips of the insole, usually with tacks, and at the toe portion with wires.

In building a shoe having my novel stirrup arch support, I do not at this stage of the operation prefer to tack the heel to the last. Instead, the heel part of the last is released and the upper 5 is thrown back so that stitching may be had to the lining without the stitching passing through the upper. The stirrup pieces 7, preferably having eyelets 8, are then secured with rows of stitching 9 which pass across the counter and extend preferably in the direction shown. In order to further support the stirrup from the lacing portion of the shoe, I also insert a line of stitching such as is indicated at 10. As stated, this stitching is done while the outer cover of the upper is thrown back so that the stitches will not pass through the outer surface of the upper.

The heel portion of the last is then opened up and the upper is pulled at its heel end down over the last and usually tacked to the last at the heel end. The upper is then usually stapled to the insole welt ridges, and the toe wires and side tacks are removed. The welt is then applied and the shoe is inseamed.

After trimming the welt and beating it down, the shank, such as is indicated at 11, is applied, and the usual filler 12 applied to the canvas surface of the insole between the welt strips. The bottom 13 is then laid and leveled, and the Goodyear stitching operation is then carried out. The shank is then beaten down, the

channel is laid, and the bottom sanding and finishing is proceeded with in the usual manner. If a wood heel is to be used, the heel seat fitting operation is proceeded with, followed by 5 the application of the heel, such as is indicated at 15.

When the assembly of the shoe on the last has been completed and the shoe has been taken off the last, lacing 16 is inserted through the 10 eyelets in the complementary meeting edges of the stirrup pieces 7. The lacing 16 may either be of flexible cords, or, in some modifications elastic cord material may be used which will give the stirrup a resilient support while at the same time providing a support which may be 15 adjustable. After the adjustment for the stirrup has been taken care of, the split portion 3 of the insole is laid back over the stirrup and the sock lining 17 may then be applied. The 20 sock lining may be adhesively secured to the split portion of the insole as desired.

Prior to the laying back of the split portion 3, tacks, such as are indicated at 18, may be applied to securely fasten down the rear end of 25 the insole to the heel; and when the split portion is laid back it will securely cover the heads of the tacks so that they will not be uncomfortable to the heel of the wearer.

Since the shoe counter is of fairly stiff material, any tendency for the stirrup to pull down 30 along the line of stitches 9 will merely cause the upper ends of the upper to be drawn inwardly, which increases the neatness and trimness of the shoe and causes no tendency to sag and make 35 unsightly wrinkles. Should it be desired to tighten up on the stirrup, it will be a simple matter to throw back the sock lining and the split portion of the insole and make a desired 40 adjustment on the cords 16.

It will thus be observed that I have provided 45 an arch supporting stirrup which in no way affects the appearance of the shoe, which requires only a small variation in the manufacturing operation of making the shoe, and which will be adjustable so that should the support tend to sag, it can be drawn up as desired.

Having thus described my invention, what I 50 claim as new and desire to secure by Letters Patent, is:

50. 1. In a shoe having a counter, a stirrup support having upper ends thereof stitched to the counter.
55. 2. In a shoe having a counter and an upper, a stirrup support having upper ends thereof stitched to the counter, said stitching being covered exteriorly by the shoe upper.
60. 3. In a shoe having a split insole, a stirrup support extending between the split portions of said insole, said shoe also having a counter, and said stirrup support secured to the upper ends of said counter.
65. 4. In a shoe having a split insole, a stirrup support extending between the split portions of said insole, said shoe also having a counter, and said stirrup support stitched to the upper ends of said counter, said shoe further having a liner, and said stitching extending through said liner and counter only.
70. 5. In a shoe having a counter, a stirrup support having upper ends thereof stitched to the counter, said stirrup support comprising two sections adjustably secured together.
75. 6. In a shoe having a counter and an insole having a split portion, a stirrup support having upper ends thereof stitched to the counter, said

stirrup extending underneath said split portion of the insole.

7. In a shoe having a split insole, a stirrup support extending between the split portions of said insole, said stirrup support comprising two sections adjustably secured together. 80

8. In a shoe having a split insole, a stirrup support extending between the split portions of said insole, said stirrup support comprising two sections adjustably secured together underneath 85 a split portion of the insole.

9. In a shoe having a counter, an upper, and a lining having an upwardly extended forward part connected to the upper above the counter and curving in over the instep, an arch support supported by the counter and connected to the lining in said upwardly extended forward part of the lining, whereby the lining and the upper partially support the arch support and the upper is further drawn in around the instep by 90 weight imposed upon the arch support. 95

10. In a shoe having a counter, an upper, and a lining connected to the upper above the counter, an arch support in said shoe, and a row of stitching, part of which passes through the 100 arch support, the lining and the counter, and another part of which passes through the arch support and the lining only.

11. In a shoe having a counter, an upper and a lining connected to the upper above the counter, an arch support in said shoe, a row of stitching, part of which passes through the arch support, the lining and the counter, and another part of which passes through the arch support and the lining only, and a second row of stitching located forwardly and upwardly from the aforementioned row of stitching, and passing through the arch support and lining only. 105

12. In a shoe having a split insole, an upper, and structure inside of and adjacent to the upper at opposite sides of the insole, an arch support comprising flexible elements supported by said structure at the respective sides of the insole and extending underneath a split portion of the insole, and lacing adjustably securing 110 said elements together under the insole, said insole forming a cushion between the lacing and the wearer's foot. 115

13. An arch supporting shoe having a split insole and structure extending up from one side of the insole, and a flexible arch supporting means connected directly to and extending from said structure underneath a split portion of the insole. 125

14. An arch supporting shoe having a split insole and structure extending up from one side of the insole, and an adjustable flexible arch supporting means connected directly to and extending from said structure underneath a split portion of the insole. 130

15. An arch supporting shoe having a split insole and structure extending up from one side of the insole, an adjustable flexible arch supporting means extending from said structure underneath a split portion of the insole, and means securing said arch supporting means to said structure, said shoe having an upper, and said securing means being exteriorly covered by the upper of said shoe. 135

16. In a shoe having a counter, an arch support, and means directly connecting said arch support to said counter, whereby said arch support is suspended from and supported by the counter. 140

17. In a shoe having a split insole, an upper, 145

and structure inside the upper and adjacent thereto, an arch support, and means directly connecting said arch support to said structure, whereby said arch support is suspended from and supported by said structure, said arch support extending underneath a split portion of the insole.
